[57] CLAIM

The ornamental design for a door handle, as shown and described.

DESCRIPTION

FIG. 1 is a front perspective view thereof;
FIG. 2 is a rear perspective view thereof;
FIG. 3 is a bottom plan view thereof;
FIG. 4 is a top plan view thereof;
FIG. 5 is a front elevational view thereof;
FIG. 6 is a rear elevational view thereof;
FIG. 7 is a right side elevational view thereof; and,
FIG. 8 is a cross-sectional view thereof taken along line 8—8 in FIG. 4.

The left side elevational view thereof has been omitted because this is a mirror image of FIG. 7.

FIGS. 3—7 are shown on a reduced scale.
